UNITED STATES PATENT OFFICE.

GEORGE C. FEDDERMAN, OF DETROIT, MICHIGAN, ASSIGNOR TO AUTO LOADING DEVICE MANUFACTURING COMPANY, OF DETROIT, MICHIGAN, A CORPORATION OF MICHIGAN.

NAIL.

Application filed September 3, 1927. Serial No. 217,412.

The invention concerns nails employed, for instance, in securing chock blocks to the floor of a freight car in the shipment of automobiles, one purpose being to provide a nail which may be limited to its drive and readily withdrawn by the comparatively low class of labor employed in such work. A further purpose is to provide a nail which, while effective in all the uses to which it 10 may be put, such as in the building of temporary forms for concrete construction, where it is desired to withdraw the nails and recover the material, will be of such construction that it may be manufactured economically and with such rapidity as to give 15 the desired quantity production to meet the demands of the trade.

In carrying out the invention the nail has been made of such form as will be capable 20 of being produced as a wire nail, it having a shoulder for limiting the distance to which it may be driven in and it having also a formation exposed above this limiting shoulder which will allow the nail to be withdrawn 25 by a claw hammer, wrecking bar, or other suitable implement.

Other objects and characteristics of the nail will be made clear by the following description.

30 The drawing shows a wire nail made according to my invention.

In this drawing 1 is the stem of the nail which is of cylindrical form, being of wire as in ordinary practice. Upset from the 35 round wire stock is a shoulder 2 presenting a flat under surface to the surface into which the nail is driven, so as to limit and determine the final position of the nail in relation thereto. This shoulder tapers upwardly at 4 to a diameter at the point 4^a of substantially that of the stem. From this 40 point 5 the upper part flares upwardly and outwardly to the extreme upper end. The upper end terminates in a flat plane at right angles to the axis of the nail and this flat surface at 6 receives the blows of the hammer or other implement used for driving the nail into place. The flared upper part 5 of the nail begins at the point where the upwardly tapered portion 4 of the limiting shoulder terminates, this construction contributing to strength and at the same time presenting a formation, which at a point in-

termidiate the lower face of the limiting shoulder and the extreme upper end of the 55 nail, is reduced sufficiently to receive the claw of the pulling implement.

By reason of the length of the upper flared portion 5 and its relation to the substantially flat shoulder at 2 which corresponds to the plane on which the nail pulling implement may rest, an ample extent of surface is afforded to receive the claw of the pulling implements, which may vary more or less as to the width between the prongs of 60 the claw. That is to say, the claw may engage the upwardly flared portion of the nail directly at its point of juncture (4^a) with the frusto-conical shoulder portion 4, or it may engage the flared member 5 at higher 65 points throughout a considerable range. The upward taper of the part 4 immediately above the flat face of the shoulder 2 lends itself to ready engagement of the claw, affording as it does an upwardly and inwardly 70 inclined surface for directing the point of the claw to its position for drawing the nail. The claw may engage the nail near the top of the flared upper end or at or near the point 4^a. This upwardly flared portion is 75 longer than the altitude of the conical portion 4 of the shoulder, or approximately two and one-half times. The extreme upper end of the flared upper portion may be the same 80 or slightly less than the diameter of the shoulder 2.

The nail is upset from round wire stock and not only is its strength not impaired as compared with a nail of ordinary construction, but by reason of the absence of a 85 head of the usual construction, i. e., one having an abrupt lateral projection and of slight altitude, there is no part to break off in driving or to pull off in drawing the nail.

Furthermore by reason of dispensing with the usual form of head having an abrupt lateral projection in respect to the shank or stem, the liability of crystallizing of the metal under the head is avoided. In the sense just described the nail of my improvement may be said to be "headless".

It will be seen from the above that the nail is upset with a lower frusto-conical portion 4 of comparatively low altitude and an upper inverted frusto-conical portion 5 105 of considerably greater altitude with their

small diameter ends equal and meeting each other. One advantage of this structure is the strength afforded against breakage under misdirected blows which may apply 5 stresses near the edge of the upper end of the nail instead of equally over the top flat surface thereof, and further the two-cone construction, one of low altitude and one of high altitude, provides space for receiving the 10 claw of the pulling instrument throughout a considerable height, and practically the entire height above the meeting point of the two cones, owing to the fact that the cone of low altitude has its side comparatively 15 sharply inclined and thus offers no obstruction to the entrance of the claw to the reduced part of the nail for performing the extracting action.

Referring to the advantage of resisting 20 stresses from a misdirected blow, it will be seen that if the side of the low altitude cone be projected it will be convergent upwardly with the opposite side of the elongated inverted cone, as indicated by the line $x-y$. 25 The base of the imaginary frusto-conical portion bounded by this line and the line x^2-y^2 extends from point x^2 to point x and this base sustains the thrust and it will be noticed that this base extends for a considerable distance laterally out beyond the 30 vertical axis of the nail to the point x , and thus prevents breakage in the plane of the flat shoulder.

The nail is especially adapted for use 35 with metal chock blocks, clips, washers or cleats as used in shipping vehicles in freight cars, where it is desired to have these devices or material used over again, it being possible to extract this nail with-

out damage to the material for its reuse. 40

It will be observed that the diameter at point 4^a is the same as the stem 1 from which point the upper part flares gradually to the upper end 6. This avoids the extra power 45 which would be required if the upper part of the head had an abrupt shoulder, and this construction also avoids crystallization in the manufacture or breaking off in the driving or pulling. Therefore this nail can be made on a light machine and requires 50 less power than would a nail having an abrupt shoulder presenting a square corner to which the metal must flow. High quantity production with comparatively little power characterizes the manufacture of 55 this nail.

I claim:

A round wire upset nail having its extreme upper end in the form of an inverted frusto-cone with the lower end of said frusto-cone 60 of a diameter substantially equal to that of the round wire and with a straight sided frusto-conical portion intermediate the said inverted frusto-conical portion and the round wire stem of the nail, the said intermediate 65 frusto-conical portion having its small diameter upper end of the same diameter as and meeting the small diameter lower end 70 of the upper inverted frusto-conical portion, the lower face of the intermediate frusto-conical portion being flat and said inverted frusto-conical portion being of considerably 75 greater altitude than the intermediate frusto-conical portion, substantially as described.

In testimony whereof, I affix my signature.

GEORGE C. FEDDERMAN.
